Primary Examiner—Prabhakar Deshmukh*Assistant Examiner*—Derrick Holland(74) Attorney, Agent, or Firm—Kenyon & Kenyon LLP(57) CLAIM

The ornamental design for box of a motor, as shown and described.

DESCRIPTION

FIG. 1 is a perspective view of an embodiment of a box of a motor showing my new design.

FIG. 2 is a bottom view thereof.

FIG. 3 is a top view thereof.

FIG. 4 is a front view thereof.

FIG. 5 is a rear view thereof.

FIG. 6 is a left side view thereof; and,

FIG. 7 is a right side view thereof.

The Figures include an illustration of the logo/written matter, "SEW," which is shown for illustrative purposes and forms no part of the claimed design.
